UNITED STATES PATENT OFFICE.

CHARLES MASCART, OF PARIS, FRANCE.

FARE-INDICATOR.

No. 856,891.

Specification of Letters Patent.

Patented June 11, 1907.

Application filed November 13, 1906. Serial No. 343,251.

To all whom it may concern:

Be it known that I, CHARLES MASCART, engineer, a citizen of the French Republic, residing at Paris, Department of the Seine,

5 France, having post-office address 27 Rue de Loudres, in the said city, have invented certain new and useful Improvements in Fare-Indicators, of which the following is a specification.

10 This invention has for its object to provide in fare indicators for vehicles and especially for motor cars, a device indicating the time during which the vehicle is kept at a stand-still due to breakdown, or accident, or other cause which occupies time which should not be charged for (which I will refer to as "breakdown") and to suspend for such time the operation of the fare indicator. The recording of stoppages of this kind is of the 15 greatest importance in the case of motor cars; it is very important that the owner of the vehicle should be in a position to know the duration of break-downs and thereby compel the driver to account for his stand-25 stills.

The accompanying drawing shows diagrammatically an arrangement in accordance with this invention.

20 The toothed wheel 1 of the clock mechanism drives through the medium of a pinion 3 a pinion 2 which operates the fare indicator 31. The pinion 3 revolves on an arbor 4 which is carried by a lever 5 and the latter is adapted to turn on the arbor 6 of the pinion 2.

35 The pinions 2 and 3 are always in gear whereas the toothed wheel 1 and pinion 3 are in gear only while the vehicle is running under normal working conditions, but are adapted to be thrown out of gear with each 40 other by shifting the lever 5. A spring 7 tends to keep the lever 5 normally in such position that the pinions 3 and 1 will gear with each other.

45 A lever 8 is capable of turning on an arbor 9 to which a pinion 10 is secured, the said lever 8 carries the arbor 11 for a pinion 12, which is constantly in gear with the pinion 10 and capable of being, by the operation of the lever 8 thrown into gear with the toothed 50 wheel 1 of the clock mechanism, or disengaged therefrom. A spring 13 tends to return the lever 8 to the position in which the pinion 12 and toothed wheel 1 are in gear.

55 The pinion 10 is provided with a pin 14 which, at each revolution of the said pinion strikes against, and raises, the lever 15 oper-

ating the totalizing device 16, the indications of which can be read through the opening 17. A spring 18 returns the lever 15 to its normal position.

60 On the arbor 6 of the pinion 2 is keyed a cam 20 which acts on a projection 21 of a lever 22. The latter is pivotally connected to a bracket 23 secured to a fixed part of the apparatus, by way of example, to the casing 24 65 of the clock mechanism. On each revolution of the cam 20 the lever 22 is oscillated, then returned to its normal position through the medium of a spring 25, which has one end connected to the lever 22 and its other end to 70 the casing 24. To prevent the projection 21 striking against the cam 20 a stop 26 is provided which limits the return motion of the lever 22. Carried on the end of the lever 22 is a pivotally mounted pawl 27 to which is attached one end of a spring 28, the other end of said spring 28 being attached to the lever 22. A guide 29 is provided for the pawl 27. The pawl 27 is adapted to act on the ratchet 75 wheel 30 of the fare indicator 31, the indications being read through an aperture 32 formed in the wall 33 of the casing of the apparatus.

80 On the shaft 34 of the totalizing device 16 for breakdowns is keyed a ratchet wheel 35 85 against which acts a pawl 36, the latter being capable of turning round its pivot in one direction, but this movement is arrested in the opposite direction through a pin 37 carried by the lever 15. A spring 38 connects the 90 pawl 36 to the lever 15. From such construction it is evident that every time the pin 14 strikes the lever 15 the pawl 36 shifts the ratchet wheel which imparts a corresponding movement to the totalizing device 16. 95

On the end of the lever 8 a link 39 is pivotally connected, and to the said link a crank 40 is pivotally attached. The crank 40 is keyed on the shaft of a drum 41 carrying on its periphery the word "breakdown."

100 The levers 5 and 8 are operated by means of a cam 19 actuated from the flagstaff 43. When the cam 19 is turned so that the lever 8 is lowered by the action of the spring 13 the drum 41 is actuated and the word "breakdown" appears in the aperture 42 formed in the wall 33 of the casing of the apparatus.

105 Under normal working conditions, the cam 19 is in the position shown in the diagram, the wheel 1 and pinion 3 being in gear and the wheel 1 and pinion 12, being out of gear.

110 The operation of the device is as follows:

When a breakdown occurs, the cam 19 is turned so that the lever 8 is no longer held in position by the said cam, and the said lever 8 is lowered by the action of the spring 13 so that the pinion 12 engages with the wheel 1 and the device 16 indicates the duration of the breakdown. At the same time the cam 19 pushes back the lever 5 and disengages the pinion 3 from the wheel 1, and the fare indicator is thrown out of action, although the clock mechanism and other gear still remains in action.

Having now particularly described and ascertained the nature of my said invention and in what manner the same is to be performed I declare that what I claim is:

1. In time and distance fare indicating apparatus, the combination with a clock mechanism, of a pair of levers, means carried by one of said levers and engaging with the clock mechanism for operating the fare indicator, means carried by the other lever and operated from the clock mechanism for actuating a device for totalizing the duration of breakdowns, and means for shifting said levers in opposite directions, causing thereby the discontinuance of the operation of the fare indicator and the operation of the totalizing device for breakdowns.
2. The combination with a fare indicator and a totalizing device for breakdowns, of a clock mechanism, shiftable motion-transmitting mechanism for conveying motion from the clock mechanism to the fare indicator, shiftable motion-transmitting mechanism for

conveying motion from the clock mechanism to the totalizing device, and means for alternately throwing said motion transmitting mechanisms out of operative connection with the clock mechanism.

3. The combination with a fare indicator and a totalizing device for breakdowns, of a clock mechanism, a shiftable lever and pinion mechanism for conveying motion from the clock mechanism to the fare indicator, a shiftable lever and pinion mechanism for conveying motion from the clock mechanism to the totalizing device, and a cam adapted to engage with the lever and pinion mechanisms for shifting them alternately out of operative engagement with said clock mechanism.

4. In an apparatus of the character described, the combination with a flag staff, of a clock mechanism, a fare indicator operated from the clock mechanism, a totalizing device for breakdowns operated from the clock mechanism, and means actuated by the flag staff for discontinuing the operation of the fare indicator by the clock mechanism and throwing into operation the totalizing device.

In testimony whereof I have hereunto set my hand in presence of two subscribing witnesses.

CHARLES MASCART.
